1

This invention relates to a process for hydrogenating certain di-(p-aminoaryl) alkanes to the corresponding di-(p-aminoalicyclic) alkanes. In a particular embodiment, it relates to a process for hydrogenating di-(p-aminophenyl) methane to di-(p-aminocyclohexyl) methane.

The di-(p-aminoalicyclic) alkane products obtained by the process of this invention may be represented by the formula

where R_1 and R_4 are of the group consisting of hydrogen atoms and alkyl radicals, R_2 is of the group consisting of hydrogen atoms and alkyl and alkoxy radicals attached to a carbon atom in the ring structure, the various R_2 substituents being the same or different and at least 3 of the R_2 substituents on any given ring being hydrogen atoms, and R_3 is a saturated divalent acyclic hydrocarbon radical containing not more than six carbon atoms. The R_1 , R_2 and R_4 substituents may be, for instance, methyl, ethyl, propyl, isopropyl, butyl, isobutyl, secondary-butyl, tertiary-butyl groups, or higher alkyl groups, or, in the case of R_2 , the corresponding alkoxy groups. These compounds are described in copending application S. N. 615,912 of William Kirk, Jr., Richard S. Schreiber, and Gerald M. Whitman, which discloses a process for their preparation comprising hydrogenation, in the presence of a ruthenium catalyst, of the corresponding di-(p-aminoaryl) alkane compounds having the general formula

wherein the substituents R_1 , R_2 , R_3 and R_4 have the same meaning ascribed to them above. The said application further discloses that, because of their structural configuration, these alicyclic diamines can exist in three or more stereoisomeric forms and that the ratio of these stereoisomers present in any given sample of diamine can be controlled to some extent by proper choice of reaction temperature and catalyst concentration during their preparation. As disclosed in copending application S. N. 720,922 of Kirk, Schreiber and Whitman, the ratio of these stereoisomers is highly significant, notably because, when condensed with a dibasic acid such as adipic acid or sebacic acid, the lower-

melting isomers yield polyamides which tend to be relatively soluble, transparent, tough and fusible, while the higher-melting isomers yield polyamides which tend to be relatively insoluble, opaque, and either high-melting or infusible.

It is an object of this invention to provide a novel process for carrying out the hydrogenation of the above-described di-(p-aminoaryl) alkane compounds to the corresponding di-(p-aminoalicyclic) alkanes. Another object of this invention is to provide a method for carrying out this hydrogenation process in such a way as to obtain di-(p-aminoalicyclic) alkane compositions containing high ratios of the lower-melting isomers. Another object is to provide a practical process for preparing di-(p-aminoalicyclic) alkane compositions of the type which can be condensed with adipic acid to produce transparent, fusible polyamides. A further object is to prepare di-(p-aminocyclohexyl) methane in a form which is liquid at room temperature. A still further object is to prepare di-(p-aminocyclohexyl) methane compositions which can be condensed with adipic acid to produce transparent, fusible polyamides. Another object is to provide a continuous process for preparing the di-(p-aminoalicyclic) alkanes. Other objects of the invention will appear hereinafter.

According to this invention, we provide a process for hydrogenating a di-(p-aminoaryl) alkane compound of the type represented by Formula II to the corresponding di-(p-aminoalicyclic) alkane compound of Formula I which comprises continuously passing the said di-(p-aminoaryl) alkane together with at least 6 mols of hydrogen per mol of aryl compound over a ruthenium dioxide (RuO_2) catalyst at a temperature within the range of 130° to 180° C. and at superatmospheric pressure. Preferably, the pressures employed are in excess of 50 atmospheres. Pressures of about 300 atmospheres have been found to be particularly satisfactory. The preferred temperature range is from 140° to 160° C., the preferred hydrogen concentration is from 50 to 100 mols of hydrogen per mol of aryl compound, and the preferred space velocity is from 0.1 to 0.6 volume of the aryl compound per volume of catalyst per hour. If desired, various volatile organic solvents may be employed. For instance, superior results are obtained when anhydrous dioxane is the solvent and the solution contains from about 5% to about 35% by weight of the aryl compound.

According to a preferred embodiment of this invention, the di-(p-aminoaryl) alkane com-

compound to which the above-described hydrogenation process is applied is di-(p-aminophenyl) methane and the product obtained is a di-(p-aminocyclohexyl) methane composition which is liquid at room temperature, i. e. about 25° C.

The process of this invention is unique in that the products resulting therefrom, upon subsequent condensation with adipic acid as well as with sebadic acid, yield polyamides which are clear, transparent and fusible. Insofar as we are aware, there is no other practical, direct process which consistently produces di-(p-aminocyclic) alkanes having these characteristics. The products obtained heretofore from the batchwise hydrogenation of the di-(p-aminaryl) alkanes of Formula II have generally yielded cloudy, opaque or infusible polyamides when condensed with adipic acid, and in order to be sure that clear, fusible polyamides would be obtained, it was necessary to subject the mixtures of diamine isomers resulting from these batchwise processes to laborious treatments in order to separate therefrom the desired geometric isomers.

It is not known with certainty why the continuous hydrogenation process of this invention yields directly these highly valuable products. The following simplified diagrams, however, will aid in explaining our theory of the process. The diagrams show schematically the three possible stereoisomers which result from the hydrogenation of di-(p-aminophenyl) methane. The long horizontal lines in the diagrams represent an edge view of a cyclohexane residue.

It is our belief that the hydrogenation of the di-(p-aminophenyl) methane results initially in a di-(p-aminocyclohexyl) methane composition consisting principally of the cis-cis and cis-trans isomers as shown above. These apparently correspond to the lower-melting isomers which yield the transparent, fusible polyamides. Generally speaking, however, the very same conditions which favor the hydrogenation seem, upon more prolonged contact, to promote isomerization of the initial product to the higher-melting (trans-trans) form. The reason for the success of the process of this invention, therefore, seems to be that conditions are employed which particularly favor the hydrogenation step, and by incorporating these conditions into a continuous process, the initial hydrogenation products are removed from contact with the hydrogenating environment before appreciable isomerization can occur.

The following examples will illustrate certain embodiments of the process of this invention and certain characteristics of the products derived therefrom.

Example 1.—This example describes a continuous process for hydrogenating di-(p-aminophenyl) methane to di-(p-aminocyclohexyl) methane. The starting material may be obtained from aniline and formaldehyde by a condensation reaction, followed by purification of the crude material either by a topping process whereby the volatile impurities are removed or by a com-

plete distillation process. The di-(p-aminophenyl) methane is dissolved in dioxane to give a solution containing 13% by weight of the diamine, and this solution is mixed at 300 atmospheres' pressure with from 50 to 100 mols of hydrogen per mol of di-(p-aminophenyl) methane. This mixture is then passed over a catalyst containing ruthenium dioxide (RuO_2) supported on charcoal at a space velocity of 0.14 volume of di-(p-aminophenyl) methane per volume of catalyst per hour. The catalyst temperature is maintained at 143° to 148° C. and 90.6% of the starting material is converted. The resulting di-(p-aminocyclohexyl) methane, which is liquid at room temperature, has a refractive index, n_{D}^{25} , of 1.5059.

Example 2.—This example describes a method for preparing a ruthenium dioxide catalyst suitable for use in the hydrogenation process of this invention. 10 parts by weight of ruthenium dioxide are fused with 50 parts of potassium hydroxide and 10 parts of potassium nitrate are added over a 5 minute period. This mixture is allowed to fuse for one hour, after which it is cooled and dissolved in 120 parts of distilled water. This solution is then poured over activated charcoal which has previously been washed with a 10% solution of potassium hydroxide and dried at 110° C. for 48 hours. The volume ratio of solution to activated charcoal is about 2:3. The impregnated charcoal is then heated to about 50° C., 15 parts of methanol are added, and the composition is dried at 110° C. The resulting catalyst contains about 4.5% by weight of ruthenium dioxide.

Example 3.—This example describes a continuous process for preparing di-(p-aminocyclohexyl) methane in high yields. A solution is prepared by dissolving 13 parts by weight of distilled di-(p-aminophenyl) methane in 87 parts of fresh, anhydrous dioxane obtained by distillation from sodium. This solution is mixed at 300 atmospheres pressure with from 50 to 100 mols of hydrogen per mol of di-(p-aminophenyl) methane and passed over a ruthenium dioxide catalyst prepared according to Example 2. The space velocity is maintained at about 0.29 volume of di-(p-aminophenyl) methane per volume of catalyst per hour, and the reaction temperature over the catalyst is maintained at 140° to 145° C. During a run of 130 hours, the amount of di-(p-aminophenyl) methane converted varies from 90 to 95% and the yields of di-(p-aminocyclohexyl) methane, based on the amount of di-(p-aminophenyl) methane employed, vary from 65 to 70%. The product, upon being purified by distillation, is liquid at room temperature and has a refractive index, n_{D}^{25} , of from 1.5057 to 1.5061.

Example 4.—This example describes the preparation of a polyamide from adipic acid and a di-(p-aminocyclohexyl) methane composition prepared according to the process of this invention. 700 Parts of distilled di-(p-aminocyclohexyl) methane obtained according to Example 3 are dissolved in 2760 parts of absolute ethanol, to which is added a hot solution of 485 parts of adipic acid in 1575 parts of absolute ethanol. The solution is allowed to cool slowly to about 6° C., and the salt, which precipitates in a yield of about 92 to 99%, is washed with absolute ethanol and dried. This salt is converted to the corresponding polyamide by heating in an autoclave under a nitrogen atmosphere. During the early heating, the autoclave is maintained under a pressure of about 250 pounds per square inch but as the temperature is raised to 306° C. the

pressure is gradually lowered to about atmospheric. Upon cooling, a clear, transparent polyamide is obtained possessing a softening point of 238° C.

While this invention has been illustrated with particular reference to the hydrogenation of di-(p-aminophenyl) methane, it is to be understood that the process may be applied to any of the compounds having the hereinbefore defined general Formula II. Included among examples of said compounds are: p,p'-diaminoditolylmethane, p,p' - diaminodianisylmethane, p,p' - diaminodiphenylmethylmethane, and di-(p-aminophenyl) ethane, to mention only a few.

The temperature range within which the process of this invention is carried out appears to be critical. At temperatures below about 130° C., the conversion of the aryl compounds are so low as to be impractical, whereas at temperatures above about 180° C., the concentration of higher-melting (trans-trans) isomers in the product becomes so great that clear, fusible, polyamides with adipic acid can no longer be obtained therefrom. In the case of di-(p-aminocyclohexyl) methane, for instance, experiments show that transparent, fusible polyamides with adipic acid can only be produced when the content of trans-trans isomer is below about 2.5% to 27%, the exact figure depending upon the relative proportions of the cis-cis and cis-trans isomers present.

The catalysts which are useful in the process of this invention are those comprising ruthenium dioxide. If desired, promoters or extenders may be employed, including, for instance, other forms of ruthenium such as sodium or potassium rutheinate. Catalyst supports which may be employed include those known in the art, such as charcoal, activated carbon, silica gel, alumina, kieselguhr, pumice, the various clays, and the like. The apparatus in which the process is carried out may be so designed that the reactants flow over the catalyst in any suitable direction including upwardly, downwardly, horizontally, etc.

Solvents which may be useful in carrying out the process of this invention include, for instance, dioxane; dioxolane; the lower alcohols such as methanol, ethanol and isopropanol; various ethers, particularly those boiling below about 100° C. such as dimethyl, diethyl and diisopropyl ether; ammonia; cyclohexane; and other volatile organic solvents. Ammonia, besides serving as a solvent, may also be useful in suppressing undesired side reactions such as deamination or the formation of non-volatile polyamines.

The products obtained according to the process of this invention are useful in the preparation of dye intermediates, germicides, surface active agents, pharmaceuticals, corrosion inhibitors, and rubber chemicals. Their outstanding characteristic, however, is that they are capable of being condensed with dibasic acids, such as adipic acid or sebasic acid, to yield clear, transparent, fusible polyamides.

Since many different embodiments of this invention may be made without departing from the spirit and scope thereof, it is to be understood that we do not limit ourselves except as defined in the appended claims.

We claim:

1. A process for preparing a di-(p-aminocyclohexyl) methane composition by hydrogenating di-(p-aminophenyl) methane, which process comprises continuously passing the said di-(p-aminophenyl) methane together with at least 6 mols of hydrogen per mol of di-(p-aminophenyl) methane over a ruthenium dioxide catalyst at a

temperature within the range of 130° to 180° C. and at superatmospheric pressure.

2. A process according to claim 1 in which the pressure employed is about 300 atmospheres.

3. A process according to claim 1 in which the temperature is within the range of 140° to 160° C.

4. A process according to claim 1 in which there is employed from 50 to 100 mols of hydrogen per mol of di-(p-aminophenyl) methane.

5. A process according to claim 1 in which the di-(p-aminophenyl) methane is passed over the catalyst at a space velocity of from 0.1 to 0.6 volume of di-(p-aminophenyl) methane per volume of catalyst per hour.

15 6. A process according to claim 1 in which the di-(p-aminophenyl) methane is passed over the catalyst in the form of a solution containing from 5% to 35% by weight of di-(p-aminophenyl) methane and the solvent employed is anhydrous dioxane.

25 7. A process for preparing a di-(p-aminocyclohexyl) methane composition by hydrogenating di-(p-aminophenyl) methane, which process comprises forming a solution of di-(p-aminophenyl) methane in dioxane, said solution containing from 5% to 35% by weight of di-(p-aminophenyl) methane, and continuously passing said solution together with from 50 to 100 mols of hydrogen per mol of di-(p-aminophenyl) methane over a ruthenium dioxide catalyst at a temperature within the range of 140° to 160° C., at a pressure in excess of 50 atmospheres, and at a space velocity of from 0.1 to 0.6 volume of di-(p-aminophenyl) methane per volume of catalyst per hour.

30 8. In a process for preparing di-(p-aminocyclohexyl) methane which comprises hydrogenating di-(p-aminophenyl) methane at superatmospheric pressure in the presence of a ruthenium dioxide catalyst and in the presence of at least six mols of hydrogen per mol of di-(p-aminophenyl) methane, the improvement which comprises passing the di-(p-aminophenyl) methane continuously over the catalyst at a space velocity of from 0.1 to 0.6 volume of di-(p-aminophenyl) methane per volume of catalyst per hour and maintaining the reaction temperature within the range of 130° to 180° C.
